BUTTER MOLD

John M. Charlton, Oakland, Calif., assignor to
 R. A. Simpson Manufacturing Company, Inc.,
 Oakland, Calif., a corporation of California

Application April 28, 1942, Serial No. 440,817

6 Claims. (Cl. 31—45)

The invention relates to molds in which soft butter or the like is placed to harden into a relatively large block preparatory to the cutting of the block into small squares suitable for packaging or dispensing, and relates more particularly to mechanism employed for opening and closing the side walls of the mold.

Butter molds of the present character are commonly in the form of a rectangular container having a bottom wall and side and end walls which are hingedly connected to the bottom wall for movement to and from a rectangularly closed position. Resilient means is provided for normally urging the walls away from their closed positions so as to facilitate the release of the hardened butter block from the mold. An object of the present invention is to provide a mechanism attached to the walls of the mold which may be quickly and easily operated to cause a movement of the mold walls to closed position against the urge of the aforesaid resilient means.

Another object of the invention is to provide a mechanism of the character above which will apply a powerful closing force and move to an over-center locked position positively insuring the retention of the mold side walls in closed position until intentionally and forcibly operated to release the walls for movement to open position.

A further object of the invention is to provide a mechanism of the character above which may be constructed of a minimum number of sturdily formed parts which will be capable of withstanding long and hard usage to which devices of the present character are subjected.

Yet another object of the invention is to provide an operating mechanism of the character described which will provide a positive opening force as well as a closing force to the mold walls.

Another object of the invention is to provide an operating mechanism of the character above having a manually engageable operating element which is so constructed and designed with respect to the mold and associated parts, that the same provides a convenient handle at one end of the mold for convenient handling of the mold.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description

may be adopted within the scope of the invention as set forth in the claims.

Referring to said drawings:

Figure 1 is a side elevation of a butter mold constructed in accordance with the present invention.

Figure 2 is an end elevation of the butter mold.

Figure 3 is a cross sectional view taken substantially on the plane of line 3—3 of Figure 2.

Figure 4 is a cross sectional view of the mold taken substantially on the plane of line 4—4 of Figure 2.

Figure 5 is an end elevation of the mold in a tilted position.

Figure 6 is an end elevation of the mold.

Figure 7 is a fragmentary cross sectional view taken substantially on the plane of line 7—7 of Figure 6.

Figure 8 is a fragmentary perspective view of a corner of the butter mold.

The butter mold depicted in the accompanying drawings comprises a rectangular container 11 having a bottom wall 12 and opposed-rectangularly related side and end walls 13 and 14, 16 and 17. All of the walls are preferably formed of wood, and the side and end walls are connected to the bottom wall in a manner to permit a limited movement of the walls relative to the bottom so that when the butter is to be removed from the mold, the side and end walls may be spread outwardly from their rectangular closed position to disengage the hardened butter block in the mold. The hinged connection between the side and end walls to the bottom wall is best shown in Figures 3 and 4 wherein the joiners of the end walls 16 and 17 to the bottom, which connection is typical, is illustrated. As here shown, the inner face of the side and end walls

are provided with a horizontal groove 18 in which is seated a corresponding tongue 19 extending from the bottom 12. A spacer cleat 21 is mounted across the base of the side and end walls which supports at its outer side a flat annular torsion producing spring member 22 and the parts are held in assembled relation by a plurality of screws 23 which extend through the spring, cleats, side and end walls and into the bottom wall and preferably fit loosely in the side and end walls to permit limited pivotal movement of these walls relative to the base. The spring member 22 extends completely around the base of the mold and is provided with an appropriate set whereby the same will normally

urge the side and end walls to their open posi-

tion. Desirably the screws 23 which extend parallel to the bottom 12 are threaded through hard wood plugs 24 fitted in the bottom to prevent stripping of the screw threads.

Mounted across the upper ends of the side and end walls and rabbeted thereto are a plurality of reenforcing cleats 26, 27, 28, 29 which are here secured in place by dowel pins 31. Preferably the cleats 28 and 29 extending across the ends 16 and 17 of the mold are somewhat longer than the normal widthwise dimension of the mold so as to overhang the ends of cleats 26 and 27 mounted on the side walls 13 and 14 and the end cleats are notched as shown in Figure 8 to receive and interlock with the ends of the side cleats. Preferably the recess 32 defining the notch in the end cleats is provided with a tapered side wall 33 which is adapted to engage a complementary tapered end wall 34 on the side cleats so that upon drawing of the end cleats towards each other to closed position of the mold, the side cleats will be also drawn toward each other to closed position. Preferably the opening movement of the walls away from each other is so limited as to constantly retain the ends of the side cleats within the recesses 32 of the end cleats, the greater separation illustrated in Figure 8 being here used merely for improved showing of the construction.

Means for drawing the walls into closed position, and more specifically means for drawing the end walls together, which in turn pull in the side walls, here consists of a crank rod 36 mounted at the outer side of cleat 28 and operatively connected by a pair of connecting rods 37 to the opposite end cleat 29. The crank rod as best seen in Figure 2 is formed adjacent its ends with offset portions 38 and 39 defining crank throws and a center offset portion 41 defining an operating handle, and is secured to the outer face of cleat 28 by straps 42 and 43 mounted adjacent the throws 38 and 39 and providing bearing caps for journaling the crank rod. The crank throws 38 and 39 are spaced apart by a distance greater than the normal spacing of the side cleats 26 and 27 and are thus positioned at the overhanging end portions of the end cleats. Formed in the end cleats directly in front of the crank throws 38 and 39 are vertical slots 44 which, as best illustrated in Figures 4 and 8, receive and permit limited vertical oscillation of the connecting rods 37. One end 46 of the connecting rods is journaled to one of the crank throws 38 and 39 by looping the end of the rod around the crank throw and the opposite end 47 is extended through a receiving opening 48 in the opposite end cleat 29 and operatively fastened to the cleat at the outer side thereof by nuts 49 threaded on the rod end 47 and supporting a washer 51 against the cleat. Preferably and as shown in Figure 4, the nuts and washers are contained in a recess 52 provided in the outer face of the cleat 29. In order to obtain a positive opening as well as a positive closing force in the operation of the crank rod 36, I prefer to mount a washer 53 on each of the connecting rods 37 against the inner face 54 of the end cleat 29 so as to impart a reverse movement to the end wall 17 upon reverse movement of the connecting rods.

Preferably the crank rod 36 is designed in such a manner in relation to the associated connecting parts that the crank throws 38 and 39 and the operating handle 41 will assume a depending position, as illustrated in Figures 2 and 4, in the open position of the mold so that upon

raising of the handle 41, the crank throws 38 and 39 will be swung outwardly away from the end cleat 28 and thereby draw the opposite end cleats 28 and 29 towards each other to closed position. The design is further arranged so that the mold walls will be drawn into their closed position as the crank throws are elevated to a dead center position with respect to their pivotal axis and the line of tension of connecting rods 37. In accordance with the present invention and as an important feature thereof, the crank throws are adapted to be moved slightly beyond dead center position as illustrated in Figure 3, so as to assume an over-center locked position. Movement beyond this over-center locked position is here prevented by the engagement of the connecting rods 37 with the top wall 56 of the cleat slots 44, as shown in Figures 3 and 8. Offset portions 45 are formed at the rods 37 and provide increased longitudinal resilience therefor. As will be understood from the foregoing, mechanical advantage is provided in the crank operation and this mechanical advantage increases to a very large amount as the crank throws approach and reach their dead center position, when the greatest force must be applied to move the side and end walls into their final closed position. In the construction here provided, only a very relatively light operating force need be applied to the handle 41 of the crank rod to produce the closing and locking action.

In the use of the butter mold, the mold walls are first closed as above and the mold is filled with soft butter. After the butter is hardened, the mold is usually inverted upon a cutting table to discharge the hardened butter block onto the table. To facilitate the inverting of the mold upon the cutting table, I prefer to round the ends 57 and 58 of the end cleats 28 and 29 as here shown in Figures 5 and 6, so that the ends of these cleats may be initially rested upon the cutting table, as shown in Figure 5, and the mold rotated to inverted position about the rounded ends of the cleats. When the mold is in inverted position upon the cutting table, the operator may engage and elevate the crank handle 41 so as to simultaneously release the mold walls from the butter block and elevate the mold from the block. In this latter movement of the crank, the connecting rods 37 are placed under compression by reason of the engagement of washer 53 with the cleat wall 54 so as to positively spread the end walls. Usually the operator after lifting the open mold from the butter block will swing the mold to the floor using the lever portion 41 as a handle, thereby dropping the mold onto the opposite end 17. With this most convenient handling of the mold, it is necessary to protect the heads 61 of screws 23 located at the base of the end walls 17, as otherwise these screw heads will become worn and mutilated and prevent withdrawal of the screws as may be necessary in the repair and upkeep of the mold. To protect these screw heads and to provide a floor engaging bumper on the mold, I provide a floor rest 62, best shown in Figures 1, 6 and 7, which is here formed of a metal strap fastened in place by the screw heads 61 and having undulated portions 63 extending outwardly well beyond the screw heads 61.

I claim:

1. In a wall closing mechanism for a butter mold of the type constructed with a bottom wall and rectangularly arranged side and end walls hingedly connected thereto and provided with top

cleats interfitted to cause movement of said walls to closed position substantially perpendicular to said bottom wall upon drawing of said end walls toward each other, a crank rod journaled for rotation on one end wall cleat and having a pair of crank throws positioned in widthwise relation adjacent to but outside of said side walls, and a pair of connecting rods carried by said end wall and secured to said other end wall cleat and extending lengthwise and to the outside of said side walls and connected to said crank throws whereby upon rotation of said crank rod said end walls may be drawn toward each other, said crank rod being provided with a laterally offset portion centrally of the length thereof adapted for manual engagement and rotation, the design of said crank rod being such that said offset portion will be positioned in depending relation in a substantially vertical plane in the open position of said mold and in a substantially horizontal plane in the closed position of said mold, said design being such that said crank throws move to and slightly over dead center position in the closed position of said mold.

2. In a wall closing mechanism for a butter mold of the type constructed with a bottom wall and rectangularly arranged side and end walls hingedly connected thereto and provided with top cleats interfitted to cause movement of said walls to closed position substantially perpendicular to said bottom wall upon drawing of said end walls toward each other, a crank rod journaled for rotation on one end wall cleat and having a pair of crank throws positioned in widthwise relation adjacent to but outside of said side walls, and a pair of connecting rods carried by said end wall and secured to said other end wall cleat and extending lengthwise and to the outside of said side walls and connected to said crank throws whereby upon rotation of said crank rod said end walls may be drawn toward each other, said crank rod being provided with a laterally offset portion centrally of the length thereof adapted for manual engagement and rotation, the design of said crank rod being such that said offset portion will be positioned in depending relation in a substantially vertical plane in the open position of said mold and in a substantially horizontal plane in the closed position of said mold, and said design being such that said crank throws move to and slightly over dead center position in the closed position of said mold, and stop means engageable by said connecting rods operating independently of the closing of said walls preventing rotation of said crank rod beyond the last mentioned position of said crank throws in the closing rotational movement of said crank rod.

3. In a wall closing mechanism for a butter mold of the type constructed with a bottom wall and rectangularly arranged side and end walls hingedly connected thereto and provided with top cleats interfitted to cause movement of said walls to closed position substantially perpendicular to said bottom wall upon drawing of said end walls toward each other, a crank rod journaled for rotation on one end wall cleat and having a pair of

crank throws positioned in widthwise relation adjacent to but outside of said side walls, and a pair of connecting rods secured adjacent one end to said other end wall cleat and extending lengthwise and to the outside of said side walls and journaled at their opposite ends to said crank throws whereby on rotation of said crank rod said end walls may be drawn towards each other, said first end cleat being formed with vertical slots aligned with and receiving said crank rods and permitting limited oscillation of the latter therein.

4. A wall closing mechanism of the character defined in claim 3 wherein the end walls of said slots are positioned to engage said connecting rods and to define the limit of movement in one direction of said rods corresponding to a rotational displacement of said crank throws to and slightly beyond dead center position with respect to said connecting rods.

5. In a wall closing mechanism for a butter mold of the type constructed with a bottom wall and rectangularly arranged side and end walls hingedly connected thereto and provided with top cleats interfitted to cause movement of said walls to closed position substantially perpendicular to said bottom wall upon drawing of said end walls toward each other, a crank rod journaled for rotation on one end wall cleat and having a pair of crank throws positioned in widthwise relation adjacent to but outside of said side walls, and a pair of connecting rods secured to said other end wall cleat and extending lengthwise and to the outside of said side walls and connected to said crank throws whereby upon rotation of said crank rod said end walls may be drawn from or toward each other and said throws will move to and stop in over-center position, each of said connecting rods having a laterally offset portion intermediate its ends affording resilient stretching of said rod.

6. In a wall closing mechanism for a butter mold of the type constructed with a bottom wall and rectangularly arranged side and end walls hingedly connected thereto and provided with top cleats interfitted to cause movement of said walls to closed position substantially perpendicular to said bottom wall upon drawing of said end walls toward each other, a crank rod formed with offset portions adjacent the opposite ends thereof to define a pair of crank throws and formed with a center offset providing an operating handle, straps secured to one end cleat and providing bearing caps journaling said crank rod on said cleat, said straps being located between said throws and said handle, said throws being located widthwise of said mold in positions outside of said side wall cleats, said end cleat being provided with vertical slots adjacent said throws, a pair of connecting rods secured adjacent one end to said other end cleat and extending lengthwise of said mold and through said slots and journaled at their opposite ends to said crank throws whereby upon rotation of said crank rod said end cleats may be drawn together.

JOHN M. CHARLTON.
